(57) **CLAIM**

The ornamental design for a drum, as shown and described.

DESCRIPTION

FIG. 1 is a perspective view of a drum showing my new design;

FIG. 2 is a top view thereof;

FIG. 3 is a bottom view thereof;

FIG. 4 is a front view thereof;

FIG. 5 is a side view thereof;

FIG. 6 is the opposite side view thereof; and,

FIG. 7 is a rear view thereof.

The broken line showing of a strap in FIG. 1 is for illustrative purposes only and forms no part of the claimed design.
